UNITED STATES PATENT OFFICE.

ROBERT E. POWERS, OF NEW YORK, N. Y., ASSIGNOR TO UNION METAL PRODUCTS COMPANY, OF CHICAGO, ILLINOIS, A CORPORATION OF DELAWARE.

COUPLER-CENTERING DEVICE.

Application filed November 15, 1922. Serial No. 601,124.

This invention relates to new and useful improvements in coupler centering devices, and the object of the invention is to provide a simple, inexpensive and durable device which will automatically return a coupler from a position of lateral displacement to a predetermined position.

A further object is to provide a centering device which will be easily and readily attached to the standard type of striker plate with a minimum amount of labor.

A still further object is to provide a device which will be positive in its action and safe under all conditions.

15 In my invention I provide a coupler shank which is link supported, the links being arranged to swing and accommodate any lateral movement of the coupler shank. The links are supported by a distance piece which 20 is fitted to a striker plate and held in position by a bolt. This bolt is provided as a positioning device for the links and also acts as a coupler shank support, should any 25 breakage occur in the swinging coupler device due to faulty workmanship. It also acts as a tie bar between the side frames of the striker plate and distributes any severe 30 stress caused by the coupler shank knocking against the side frames evenly between the side frames, thus strengthening the construction.

In the drawings which illustrate the invention.

Figure 1 is a front elevation of the device 35 attached to a distance piece which is slidably mounted on a striker plate.

Figure 2 is a sectional elevation taken on the line 2—2 Figure 1.

Figure 3 is a front elevation of the device 40 attached to a distance piece which is riveted to a striker plate.

Figure 4 is a sectional elevation of the device taken on the line 4—4 Figure 3.

Figure 5 is a front elevation of the device 45 attached to a one piece striker plate.

Figure 6 is a sectional elevation taken on the line 6—6 Figure 5.

Referring more particularly to the drawings, 11 designates the end sill of a car to which is attached a striker plate 12, provided with a space 13 in which the coupler shank 14 may move vertically and horizontally. Between the side frames 15 of the striker plate is a distance piece 17. The dis-

tance piece can be made as in Figures 1 and 2, that is slidably mounted on the ledges, 16 and held in position by a bolt 18 passing through the side frames 15 or it can be made as shown in Figures 3 and 4, (i. e.) riveted to the side frames 15 by the rivets 18a. A still further modification can be made by casting the distance piece integral with the striker plate as shown in Figures 5 and 6. Bearings or lugs 19 are cast in the distance piece, see Figures 1 and 3, or cast directly to the side frames as shown in Figure 5 for supporting the swivelling links 20. The links are provided with trunnions 21 at one end, said trunnions being arranged to swivel in the bearings 19. The other end of the links have trunnions 22 on which is carried the coupler shank support 23. The coupler shank is placed between the lugs 24, cast integral with the support 23, so that any movement of the coupler shank will be transmitted to the support 23 which will swivel on the links 19. In Figures 1, 2, 3 and 4 the distance piece 17 passes through an aperture 26 in the support 23. In Figures 5 and 6 the support 23 passes through an aperture 26b in the distance piece.

In the drawings I have shown the centres of the bearings 19 supporting the link 21 closer together than the bearings 25 of the support 23. The bearings 25 engage with the link trunnions 22. This causes the links to make a slight angle with the vertical when the device is in the normal position. Any lateral movement of the coupler shank support brings one link nearer the vertical position, but increases the angle of the other or vice versa, and immediately the coupler is released the device returns to its normal position. The bolt 18 in Figure 1 is also arranged to support the coupler should any breakage occur due to faulty workmanship. It is also used as a locking device to keep the links in position. Other modifications may be made in the device without departing from the spirit of the invention.

Having thus described my invention, what I claim is:—

1. In a coupler centering device, a striker plate, ledges on said striker plate, a distance piece supported by said ledges, bearings in the distance piece, links oscillatably mounted in said bearings and depending therefrom, a coupler shank support oscillatably mount-

- ed on said links, and means for holding the links and the distance piece in position.
2. In a coupler centering device, a striker plate, a distance piece attached to said striker plate, bearings in said distance piece, links oscillatably mounted in said bearings, and depending therefrom, a coupler shank support oscillatably mounted on said links and means for holding the links in position.
- 5 3. A coupler centering device comprising a striker plate including spaced side frames, hooks supported at the lower end of said frames, links swingingly suspended from said hooks, a coupler carrier mounted between said side frames and provided with spaced depending wall portions supported by the lower portions of said links and a distance piece extending between the lower portions of the said frames and located intermediate the depending wall portions of the carrier.
- 10 4. In a coupler centering device comprising a striker having spaced side frames, a distance piece spanning the distance between the frames and attached thereto, a coupler support, and links swingably suspending the support from the distance piece independently of the striker.
- 15 5. In a coupler centering device comprising a striker having spaced side frames with a ledge on each frame, a distance piece supported upon said ledges and spanning the distance between the frames and attached thereto, a coupler support, and links swingably suspending the support from the distance piece independently of the striker.
- 20 6. In a coupler centering device comprising a striker having spaced side frames, a distance piece spanning the distance between the frames and attached thereto, a coupler support straddling the distance piece, and links swingably suspending the support from the distance piece independently of the striker.
- 25 7. In a coupler centering device comprising a striker having spaced side frames, a distance piece spanning the distance between the frames and attached thereto by a bolt
- 50 passing through said frames and said piece, a coupler support, and links swingably suspending the support from the distance piece independently of the striker, said bolt forming an emergency coupler support.
- 55 8. In a coupler centering device comprising a striker having spaced side frames, a distance piece spanning the distance between the frames and attached thereto by a bolt passing through said frames and said piece, a coupler support, and links swingably suspending the support from the distance piece 60 independently of the striker, said bolt so positioned as to retain the coupler support, distance piece and links in proper relative relation.
- 65 9. In a railway car, the combination of a striker, a distance piece rigidly attached thereto, and a coupler support swingably suspended from said distance piece independently of said striker.
- 70 10. In a railway car, the combination of a car part, an emergency coupler support comprising spaced apart walls, a coupler support positioned between said walls so as to permit its movement laterally of the car, and links swingably suspending the coupler support 75 from the emergency coupler support.
- 75 11. In a railway car, the combination of a car part, an emergency coupler support comprising spaced apart walls, a coupler support positioned between said walls so as to 80 permit its movement laterally of the car and so as to restrict its movement longitudinally of the car, and links swingably suspending the coupler support from the emergency coupler support.
- 85 12. A car coupler centering device comprising a coupler support swingably suspended from a car part by links having oppositely disposed trunnions at each end, the trunnions at one end of each link being spaced further apart than the trunnions at the opposite end of the same link.

In witness whereof, I have hereunto set my hand.

ROBERT E. POWERS.
